No. 731,994.

PATENTED JUNE 23, 1903.

L. G. CANTRELL.
ADJUSTABLE TRESTLE.
APPLICATION FILED AUG. 9, 1902.

NO MODEL.

UNITED STATES PATENT OFFICE.

LOUIS GORBY CANTRELL, OF NASHVILLE, TENNESSEE, ASSIGNOR OF
ONE-HALF TO JOSEPH M. JOHNSON, OF NASHVILLE, TENNESSEE.

ADJUSTABLE TRESTLE.

SPECIFICATION forming part of Letters Patent No. 731,994, dated June 23, 1903.

Application filed August 9, 1902. Serial No. 119,017. (No model.)

To all whom it may concern:

Be it known that I, LOUIS GORBY CANTRELL, a citizen of the United States, residing at Nashville, in the county of Davidson 5 and State of Tennessee, have invented a new and useful Adjustable Trestle, of which the following is a specification.

This invention relates generally to trestles, and more particularly to an adjustable trestle particularly adapted for use of painters, carpenters, and the like.

The object of the invention is to provide a simple and durable construction of trestle which can be quickly and easily adjusted and 15 one which can be folded into a very small compass when not in use.

Another object is to provide a trestle which can be used either singly or in series.

With these objects in view the invention 20 consists in the novel features of construction, combination, and arrangement, all of which will be fully described hereinafter and pointed out in the claim.

In the drawings forming part of this specification, Figure 1 is a perspective view of a trestle constructed in accordance with my invention. Fig. 2 is a detail view showing the manner of connecting the stringer to the supporting-standards. Fig. 3 is a sectional view 25 showing such connection. Fig. 4 shows a slightly-modified construction of supporting-standards. Fig. 5 is a detail of such modification. Fig. 6 is a view showing construction employed when the trestle is arranged in 30 series. Fig. 7 is a view showing the extensible stringer.

In carrying out my invention I employ a horizontal bar or stringer A, having the vertical end pieces A' connected to its ends, said 35 pieces being braced by means of the oblique braces A². Ordinarily this stringer A consists of a single piece; but, if desired, it may be made in two parts, the inner ends having loops A³ connected thereto and through which 40 the extension-bar A⁴ slides. By this construction the stringer can be extended or contracted, as desired. The vertical end pieces A' are each provided with the plurality of depending hooks B, which are adapted to engage

the horizontal pins B', which extend across 50 the grooved portion of the standards C, said groove being a compound one, the inner portion being adapted to receive the hooks B, while the outer portion of said groove is intended to receive vertical end pieces A'. The 55 standards C are supported by means of the inclined legs C', connected at their upper ends to the upper end of the standard, the lower ends of said legs being connected by means of a cross-piece C² and upon which the 60 lower end of the standard rests, as most clearly shown in Fig. 1. Each end piece A' has a U-shaped clamp D pivoted thereto at D', the free ends of said clamp being adapted to engage the depending fastening-plates D², secured upon opposite sides of the standard C, and by reference to Fig. 3 it will be noted that 65 the clamps and plates are arranged intermediate the hooks and pins. After the hooks have been brought into engagement with the 70 pins the clamps are turned so as to bring their free ends into engagement with the plates D², and in this manner the stringer is securely locked to the standard, and inasmuch as there are a plurality of pins and also 75 a plurality of plates it is obvious that the stringer can be adjusted to any desired height between the standards.

In Fig. 6 I have shown a double standard or one having both faces grooved, so that two 80 stringers are adapted to be connected thereto.

In Fig. 4 I have shown the standards supported by means of legs C³, pivotally connected to a plate C⁴ and provided with claw-feet C⁵ in order to avoid slipping. This construction I have found particularly adapted for the use of bricklayers, and this form of support can be used in connection with the other form, if so desired, or both ends of the stringer may be supported by a standard held in this 90 manner. The other portions of the standard are exactly the same, and the operations of the various parts are identical.

The construction and operation as well as the advantages of a trestle constructed in 95 accordance with my invention will be apparent to every one skilled in the art to which it appertains.

Having thus fully described my invention, what I claim as new, and desire to secure by Letters Patent, is—

In a trestle, the combination with a stringer, of end pieces secured thereto, standards having compound grooves in their inner faces, horizontal pins arranged transversely in the

inner grooves, hook members carried by the end pieces and adapted to engage said pins, and supporting-legs secured to the standards. 10

LOUIS GORBY CANTRELL.
